CABINET HAVING AUTOMATICALLY SHIFTABLE MIRROR

Julius H. Hirshbergh, Los Angeles, Calif.

Application May 9, 1945, Serial No. 592,855

11 Claims. (Cl. 312—186)

1

My invention relates to a medicine cabinet, or the like.

One of the principal objects of this invention is to provide a cabinet of this class, adapted to contain a movable mirror which is moved outwardly toward or over the opening of the cabinet as the closure therefor is opened, such as when the door or doors for the cabinet is or are opened.

Another important object of this invention is to provide a cabinet of this class in which the mirror is urged or forced outwardly when the closure means is opened, the opening of the latter permitting such outward moving of the mirror.

An important object also of this invention is to provide a mirror in a cabinet of this class which is forced inwardly to the rear portion of the cabinet when a door is closed over the opening of the cabinet, and particularly by shelves carried by the inner side of the door.

A further important object of this invention is to provide a cabinet whereby the mirror is yieldably mounted to reduce to a minimum the possibility of breaking the mirror.

A still further important object of this invention is to provide a structure of this class whereby the door or doors are automatically opened when merely unlatched.

With these and other objects in view, as will appear hereinafter, I have devised a medicine or similar cabinet, having certain novel features of construction, combination, and arrangement of parts and portions, as will be hereinafter described in detail and particularly set forth in the appended claims, reference being had to the accompanying drawings, and to the characters of reference thereon, which form a part of this application, in which:

Fig. 1 is a front view of a medicine cabinet with the door open, and with a portion of the mirror broken away to facilitate the illustration of the mounting therefor within the cabinet;

Fig. 2 is a transverse sectional view thereof, taken through 2—2 of Fig. 1, showing by dotted lines the door and mirror partly closed, or inwardly shifted positions;

Fig. 3 is a sectional elevation thereof, taken through 3—3 of Fig. 1; and

Fig. 4 is a sectional view, similar to that shown in Fig. 2, on a reduced scale, showing my cabinet in a slightly modified form of construction.

The cabinet, designated 1, may be installed in a building wall, designated 2, and in conventional building construction. The cabinet has a door 3 hinged at one edge as in conventional construc-

2

tion. In this instance, however, a mirror 4 is provided within the cabinet and shelves 5, for supporting the usual medicine containers, toiletries, articles, and the like, designated 6, are provided on the door 3.

The mirror 4 is movably mounted within the cabinet so that it assumes a position over the opening 1^a, when the door 3 is open, or inward position, shown by dotted lines in Fig. 2, when the door is closed. For supporting the mirror I have shown pairs of links 7 at the backside of the mirror and near the upper and lower portions thereof. These links are shown as being located and operated in horizontal planes. Each pair of links consists of members 7^a and 7^b which are pivotally connected intermediate their ends. One end of each link is slidably mounted on a transverse rib 8 at the back of the cabinet and the other end of each link is slidably mounted on a rib 9 at the back of the mirror. These ends are pivotally connected to these ribs by bolts or pins 10 and 11 extending through longitudinal slots 8^a and 9^a in the ribs 8 and 9. As shown, the link 7^a is positioned at the underside of the ribs while the link 7^b is positioned over the top side of the ribs. The lateral edges 4^a of the mirror are spaced only slight distances from the sides of the cabinet so as to reduce lateral movement of the mirror to a minimum. Such construction permits the mirror to be moved inwardly and outwardly with the face of the mirror at all times parallel with the opening.

Surrounding the opening 1^a of the cabinet is a frame 1^b which provides a frame for the mirror and means for limiting the outward movement thereof.

Within the cabinets are provided compression springs 12, which normally urge the mirror to the outward position when the door 3 is open.

The upper and lower shelves 5' and 5'' are curved, as shown best in Fig. 2, and thereby provide cam surfaces for engaging the face of the mirror when the door is being closed and force the mirror inwardly as the door is shifted to its fully closed position. Such curved outer edge of the shelves also provides means for permitting the gradual outward shifting of the mirror when the door is opened. Such construction also permits the outward shifting or opening of the door when it is only slightly unlatched.

At the free edge of the door is shown a latch 13, for holding the door in a closed position.

The modified structure, shown in Fig. 4 is very similar to that shown in Fig. 2, except that two half doors 21 and 22 are provided on the inside

surfaces of the doors, and the shelves 23 and 24, respectively carried thereby, are similarly curved at their outer edges, as described above.

Though I have shown and described a particular construction, combination, and arrangement of parts and portions, and a certain modification thereof, I do not wish to be limited to the same, but desire to include in the scope of my invention the construction, combination, and arrangement substantially as set forth in the appended claims.

I claim:

1. In a structure of the class described, a cabinet open at its outer side, a mirror movably mounted in the cabinet and shiftable within the cabinet from the inner to an outer position over the opening, means for supporting the mirror in the cabinet to facilitate such shifting, and a door for the cabinet, said door being provided with means to shift the mirror inwardly when the door is closed.

2. In a structure of the class described, a cabinet open at its outer side, a mirror movably mounted in the cabinet and shiftable within the cabinet from the inner to an outer position over the opening, means for supporting the mirror in the cabinet to facilitate such shifting, and a door for the cabinet, said door being provided with shelves having curved edges adapted to engage and to shift the mirror inwardly when the door is closed.

3. In a structure of the class described, a cabinet open at its outer side, a mirror movably mounted in the cabinet and shiftable within the cabinet from the inner to an outer position over the opening, means for supporting the mirror in the cabinet to facilitate such shifting, spring means for normally urging the mirror to its outer position when the door is open, and a door for the cabinet, said door being provided with means to shift the mirror inwardly when the door is closed.

4. In a structure of the class described, a cabinet open at its outer side, a mirror movably mounted in the cabinet and shiftable within the cabinet from the inner to an outer position over the opening, means for supporting the mirror in the cabinet to facilitate such shifting, spring means for normally urging the mirror to its outer position when the door is open, and a door for the cabinet, said door being provided with shelves having curved edges adapted to engage and to shift the mirror inwardly when the door is closed.

5. In a structure of the class described, a cabinet open at its outer side, a mirror movably mounted in the cabinet and shiftable within the cabinet from the inner to an outer position over the opening, pairs of pivotally connected links pivotally connecting the back of the mirror at opposite edge portions to the back of the cabinet to facilitate such shifting, and a door for the cabinet, said door being provided with means to shift the mirror inwardly when the door is closed.

6. In a structure of the class described, a cabinet open at its outer side, a mirror movably mounted in the cabinet and shiftable within the cabinet from the inner to an outer position over the opening, pairs of pivotally connected links pivotally connecting the back of the mirror at opposite edge portions to the back of the cabinet to facilitate such shifting, and a door for the cabinet, said door being provided with shelves hav-

ing curved edges adapted to engage and to shift the mirror inwardly when the door is closed.

7. In a structure of the class described, a cabinet open at its outer side, a mirror movably mounted in the cabinet and shiftable within the cabinet from the inner to an outer position over the opening, pairs of pivotally connected links pivotally connecting the back of the mirror at opposite edge portions to the back of the cabinet to facilitate such shifting, and a door for the cabinet, said door being provided with means to shift the mirror inwardly when the door is closed.

8. In a structure of the class described, a cabinet open at its outer side, a mirror movably mounted in the cabinet and shiftable within the cabinet from the inner to an outer position over the opening, pairs of pivotally connected links pivotally connecting the back of the mirror at opposite edge portions to the back of the cabinet to facilitate such shifting, and a door for the cabinet, said door being provided with shelves having curved edges adapted to engage and to shift the mirror inwardly when the door is closed.

9. In a structure of the class described, a cabinet open at its outer side, a mirror movably mounted in the cabinet and shiftable within the cabinet from the inner to an outer position over the opening, means for supporting the mirror in the cabinet to facilitate such shifting, and a pair of doors pivotally mounted at the opposite sides of the cabinet, said doors being provided with means to shift the mirror inwardly when the doors are closed.

10. In a structure of the class described, a cabinet open at its outer side, a mirror movably mounted in the cabinet and shiftable within the cabinet from the inner to an outer position over the opening, means for supporting the mirror in the cabinet to facilitate such shifting, and a pair of doors pivotally mounted at the opposite sides of the cabinet, said doors being provided with means to shift the mirror inwardly when the doors are closed.

11. In a structure of the class described, a cabinet open at its outer side, a mirror movably mounted in the cabinet and shiftable within the cabinet from the inner to an outer position over the opening, means for supporting the mirror in the cabinet to facilitate such shifting, spring means for normally urging the mirror to its outer position when the door is open, and a pair of doors pivotally mounted at the opposite sides of the cabinet, said doors being provided with means to shift the mirror inwardly when the doors are closed.
